UNITED STATES PATENT OFFICE.

JOHN J. HENNESSEY, OF MILWAUKEE, WISCONSIN.

FRICITION DRAFT-RIGGING FOR RAILROAD-CARS.

SPECIFICATION forming part of Letters Patent No. 717,677, dated January 6, 1903.

Application filed November 5, 1902. Serial No. 130,136. (No model.)

To all whom it may concern:

Be it known that I, JOHN J. HENNESSEY, a citizen of the United States, residing in Milwaukee, in the county of Milwaukee and State 5 of Wisconsin, have invented a new and useful Improvement in Friction Draft-Rigging for Railway-Cars, of which the following is a specification.

My invention relates to friction draft-rigging for railway-cars, and more particularly to the construction of the side plates or stop-castings employed therein.

The object of my invention is to provide a friction draft-rigging of a simple, strong, and durable construction, in which the opposing or engaging surfaces between the transversely or vertically movable friction-block and the side plates or stop-castings shall be composed of suitable metals of different kinds or characters to secure proper wearing and friction surfaces and increase the durability of the draft-rigging as a whole.

My invention consists in the novel construction of parts and devices and in the novel 25 combinations of parts and devices herein shown and described and by which this object or result is accomplished.

In the accompanying drawings, forming a part of this specification, and in which similar letters of reference indicate like parts throughout the several figures, Figure 1 is a vertical section of a friction draft-rigging embodying my invention, taken on line 11 of Fig. 2. Fig. 2 is a plan view, partly in horizontal section, the sectional part being on line 22 of Fig. 1. Fig. 3 is an enlarged detail horizontal section of one of the side plates or stop-castings. Fig. 4 is a side elevation of the same. Fig. 5 illustrates a modification, 40 and Fig. 6 illustrates my invention as applied to a side plate or stop-casting for use in a friction draft-rigging having two transversely arranged springs and friction-blocks arranged tandem.

In the drawings, A represents the draft-timbers, A' the center sills, A² the cross-sill, A³ the buffer-block, A⁴ the buffer-plate, A⁵ the carry-iron, B the draw-bar, and B' the coupler, these parts being all of any suitable 45 construction.

D is the sliding friction-draw-bar extension

or draft-iron, the same being directly in line with the draw-bar and connected thereto by a clip or yoke b, passing through an eye d in the draw-bar extension or draft-iron. The 55 draft-iron D has a straight friction-face d² at one side, preferably its upper side, and double friction-faces d³ d⁴ on its opposite or lower side.

F F are the side plates or stop-castings of 60 the draft-rigging, the same fitting between the draft-timbers and being securely attached thereto by bolts f. The straight friction-face d² of the draft-iron is in sliding frictional engagement with the stationary friction face or 65 plate G on the stop-castings F, the same being preferably formed in a separate piece therefrom, but securely anchored thereto.

H is the transversely-movable friction-block, the same having double-incline friction-faces h h', engaging corresponding friction-faces d³ d⁴ on the draft-iron. The friction-block H is also provided with an integral downwardly-projecting flange or cup h³ to receive and guide the spring K, which acts 75 against the block H and is supported in a removable spring seat or cup K, secured to the stop-castings F by cotter-bolts K². The vertically or transversely movable friction-block H is guided in its transverse or vertical movement and held from longitudinal movement by vertical guides or shoulders f² on the side plates or stop-castings F, which are also provided with inserted wearing pieces or blocks 80 f³ of different material from the side plates or stop-castings and from the transversely-movable block H to increase the wearing qualities and durability of the parts. The inserted pieces or blocks f³ are secured in place by rivets f⁴ and are preferably of the 85 form illustrated in Figs. 3 and 4 for a single-spring draft-rigging or in Fig. 6 for a double-spring draft-rigging, so as to give a wearing-face of different material for both corner-faces of the block H and also a wearing-face f⁵ for the vertical face of the draft-iron. If desired, however, the inserted wearing pieces or blocks f³ may be of simple angle form, (illustrated in Fig. 5,) in which case the side plate F is provided with a shoulder or rib f⁶ to form a recess or socket to receive the inserted piece f³. As illustrated 90 95 100

in Figs. 3, 4, and 6, the inserted pieces f^3 have a flange or shoulder f^7 to embrace the upright guide f^2 of the side plate or stop-casting.

The draft-iron D is provided with shoulders or stops d^5 , which engage corresponding shoulders or stops f^8 on the side plates or stop-castings to limit the longitudinal movement of the draft-iron and draw-bar connected thereto.

10 I claim—

1. In a friction draft-rigging, the combination with a draw-bar, of a draft-iron in line therewith, having a straight friction-face on one side and double-incline friction-faces on

15 the opposite side, a transversely-movable friction-block having double-incline friction-faces engaging the double-incline friction-faces on the draft-iron, a transversely-arranged spring acting against said friction-

20 block, and side plates or stop-castings having a straight friction face or plate with which the straight friction-face on the draft-iron is in sliding frictional engagement, and provided with upright or transverse guide-surfaces for said transversely-movable friction-block of different material from the side 25 plates or stop-castings, substantially as specified.

2. In a friction draft-rigging, the combination with a draw-bar, a draft-iron in line therewith having a straight friction-face on one side and double-incline friction-faces on the opposite side, and a transversely-movable friction-block, of side plates or stop-castings

secured to the draft-timbers and having 35 guides extending transversely to the draft-iron for said friction-block provided with inserted wearing pieces or blocks of different material, substantially as specified.

3. In a friction draft-rigging, the combination with a draft-iron having a straight friction-face on one side and double-incline friction-faces on the opposite side, of side plates or stop-castings secured to the draft-timbers and provided with guides extending transversely to the draft-iron having inserted wearing faces or blocks of different material, substantially as specified.

4. In a friction draft-rigging, the combination with a draft-iron having a straight friction-face on one side and double-incline friction-faces on the opposite side, of a transversely-movable friction-block having double-incline friction-faces, a transversely-arranged spring acting against said block, side plates 55 or stop-castings, a stationary friction face or plate thereon engaging the straight friction-face of the draft-iron, and provided with upright guides for said transversely-movable friction-block, said guides having inserted 60 wearing pieces or blocks of different material, furnished with a face engaging the vertical side of the draft-iron, substantially as specified.

JOHN J. HENNESSEY.
